SUPPORT TRAY

Ralph E. Roper, Indianapolis, Ind., assignor to Wallace
Expanding Machines, Inc., Indianapolis, Ind.

Filed Jan. 7, 1972, Ser. No. 216,332

Term of patent 14 years

Int. Cl. D12—16

U.S. Cl. D12—53

Fig.1.

Fig.2.

Fig.3.

FIG.4.

FIG.5.

FIG.6.

FIG. 1 is a top plan view of a support tray showing my new design.

FIG. 2 is a side view thereof as viewed in the direction of arrows 2—2 of FIG. 1.

FIG. 3 is an end view thereof as viewed in the direction of arrows 3—3 of FIG. 1.

FIG. 4 is a bottom plan view thereof as viewed in the direction of arrows 4—4 of FIG. 2.

FIG. 5 is an enlarged fragmentary cross sectional view thereof, as viewed in the direction of arrows 5—5 of FIG. 1.

FIG. 6 is an enlarged fragmentary cross sectional view thereof as viewed in the direction of arrows 6—6 of FIG. 1.

I claim:

The ornamental design for a support tray, as shown.
